UNITED STATES PATENT OFFICE.

DICKRAN M. SARKISIAN, OF FOREST HILLS, NEW YORK.

SWIVELED RING PULLEY.

Application filed March 3, 1923. Serial No. 622,487.

This invention relates to ring pulleys such as are particularly adapted to be used in connection with curtain rods supporting curtains which are adapted to be drawn or retracted through the instrumentality of suitably arranged curtain operating cords.

An important object of the invention is to so construct a device of the class mentioned as to enable it to be readily associated with certain types of curtain fixtures without necessitating any change in the construction of the device itself or the type of fixture with which it is desired to associate the same.

15 A further object of the invention is to so construct and anchor the above mentioned pulleys that they may be allowed to readily assume such positions as will permit their freedom of operation under varying conditions incident to the drawing or retracting of the curtain through the instrumentality of the curtain operating cords associated therewith.

20 Other objects and certain advantages of the invention will become apparent from the following description when taken in connection with the accompanying drawings in which—

25 Figure 1 is a plan view of a plurality of curtain rods with which my invention is associated.

Figure 2 is a vertical sectional view taken on line 2—2 of Figure 1, certain elements thereof being shown in elevation.

30 Figure 3 is an end view of the type of bracket shown at the left in Figure 2, the bracket being viewed from the right therein.

Figure 4 is a view similar to that of Figure 3 showing the bracket appearing at the right in Figure 2 and as viewed from the left therein.

35 In the drawings wherein for the purpose of illustration is shown what I at present consider the preferred form of my invention, the numeral 5 indicates a suitable support such, for example, as a window frame to which is secured a pair of curtain rod supports 6 of conventional design, with which is associated a curtain rod 7. The device embodying my invention makes possible the association of a second curtain rod 8 with the first mentioned rod without necessitating any change or alteration thereof, and comprises a pair of curtain rod supporting brackets 9 having feet or base por-

tions 10, the brackets 9 being provided at their outer ends with sockets 11 into which the ends of the rod 8 are adapted to fit. In order that the brackets 9 may be readily associated with the supports 6 I have provided the feet 10 with notches 12 adapted to receive the supports 6 so that the same screws 13 which are utilized for retaining the supports 6 in position may be employed to anchor the brackets 9 in a superimposed relation upon the supports 6, as shown most clearly in Figure 1. The curtain rod 8 is adapted to carry a plurality of slidable curtain rings 14 of conventional design, adapted to suspend a pair of curtains or portières 15 which may be drawn or retracted through the instrumentality of a curtain cord 16 so associated with the curtain rings 14 as to effect their desired operation, as will be readily appreciated by those skilled in the art to which my invention pertains.

According to the usual practice the curtain cord is passed over pulleys which are so mounted that so-called jamming of the curtain cord not infrequently occurs due to the fact that the pulleys are fixed with respect to their respective supports and are therefore unable to accommodate or adjust themselves to varying conditions incident to the operation of the curtain cord. To overcome this objection I have employed pulleys 17 and 18 mounted in yokes 19 and 20, respectively, which are swiveled to the depending arms 21 carried by the brackets 9. The yokes 19 and 20 are substantially identical except as to size, the yoke 20 being sufficiently wide to accommodate a pair of pulleys 18 over which the depending ends 22 of the curtain cord are adapted to operate, whereas the yoke 19 is of such size as to accommodate only a single pulley shown most clearly in Figures 2 and 3. These yokes being swiveled or pivotally connected to the depending arms 21 of the brackets 9 by means of rivets 23 and 24, respectively, are permitted to slightly move with respect to the arms 21 to meet varying conditions incident to the operation of the curtain cord 16. For example, under certain conditions and with certain size curtain rings 14 the yoke 19 may assume its horizontal position shown in Figure 2, whereas under other conditions and when other sizes of curtain rings are employed the pulley 17 may tend to assume a vertical position; and the same is equally true of the yoke 20 with which are

associated the pulleys 18. This self adjustment of the yoke 20 to prevent jamming of the curtain cord 16 is particularly desirable when a pull or stress is applied to the depending ends 22 of the curtain cord in any other than a perpendicular or substantially perpendicular line. It is not unusual for one to grasp an end of the curtain cord 16, when desiring to draw or retract the curtains 15, and exert a pull upon the cord at a relatively steep angle with respect to the vertical plane of the depending curtains 15. Under such conditions of operation the stress exerted upon the curtain cord 16 is such as to move the yoke 20 from its vertical position shown in Figures 2 and 4 so that the disposition of the pulley 18 will correspond to the inclination of the depending end or ends to which the operating strain has been applied.

Having thus described my invention, I claim:

1. In combination, a support, a curtain rod support extending outwardly therefrom and carrying a curtain rod at its outer end, a curtain rod bracket having a foot provided with a notch within which said curtain rod support is received, means for securing said foot to said curtain rod support, a second curtain rod supported by said bracket, and means supported by said bracket, for operating a curtain on said second curtain rod.
2. The combination with a curtain rod support, of a curtain rod bracket having a foot provided with a notch adapted to receive said support, and a pulley swiveled to said bracket.
3. The combination with a pair of curtain

rod supports, of a pair of brackets having feet provided with notches adapted to receive said supports, a curtain rod associated with said brackets, curtain supporting elements slideable upon said rod, a curtain cord associated with said curtain supporting elements for effecting a sliding movement thereof upon said rod, yoke supporting arms carried by said brackets, pulleys over which said curtain cord is adapted to operate, said pulleys being swiveled to said arms whereby self adjustment thereof is permitted to meet varying conditions incident to the operation of said curtain cord.

4. The combination with a pair of curtain rod supports, of a pair of brackets having feet provided with notches adapted to receive said supports, a curtain rod associated with said brackets, curtain supporting elements slideable upon said rod, a curtain cord associated with said curtain supporting elements for effecting a sliding movement thereof upon said rod, yoke supporting arms carried by said brackets, yokes swiveled to said arms, pulleys associated with said yokes and adapted to receive said curtain cord, said pulleys being adapted for self adjustment by reason of the swivel connection between said yokes and brackets to meet varying conditions incident to the operation of said curtain cord.

5. The combination with a curtain rod support, of a curtain rod bracket having a foot provided with a notch adapted to receive said support, an arm carried by said bracket, and a pulley swiveled to said arm.

In testimony whereof, I have affixed my signature to this specification.

DICKRAN M. SARKISIAN.
